PAPER NOVELTY

Henry E. Luhrs, Shippensburg, Pa.

Application July 3, 1936, Serial No. 88,747

5 Claims. (Cl. 229—8)

This invention relates to a class of articles of which so-called "holiday novelties" are examples. The article to be described herein embodies the invention in what is called an Easter basket, i. e. a collapsible container which when expanded and brought to final form exhibits a "nest" providing a bed simulating grass upon which may be deposited the familiar Easter eggs.

The principal object of the invention is to provide a "nest" material or bed for such a basket or for other uses which shall, by a novel method hereinafter described, be readily and cheaply made from or incidentally to the manufacture of what is known as honeycomb paper; and another object is to provide for the assembly of such a nest or bed with and between relatively movable members, which may be walls of a preferably collapsible container box, or basket, so that when the container is collapsed for shipping with the said walls brought together, the "nest" will likewise be collapsed and in a relatively flattened and compact mass between them; and so that when the container is expanded the "nest" will likewise be expanded and substantially 25 cover the bottom of the box or basket.

Other features, objects and advantages of the invention will become apparent by reference to the following detailed description of the accompanying drawings, wherein:

30 Fig. 1 illustrates in elevation a form of Easter basket or box in collapsed form, with parts broken away to reveal the imitation grass;

Fig. 2 is a view taken at right angles to the showing of Fig. 1;

35 Fig. 3 shows the box expanded and set up, with the contained honeycomb likewise expanded;

Fig. 4 is a section taken on the line 4—4 of Fig. 3;

40 Fig. 5 is a partial sectional view taken on the line 5—5 of Fig. 4;

Fig. 6 is the elevation showing one of the lengths of paper which go to make up the honeycomb, and showing the slitting of the upper portion of such length of paper and the glue areas 45 on the lower portion thereof;

Fig. 7 shows a triangular form of box or nest;

Fig. 8 is an elevation, with parts broken away, showing the assembly of Fig. 7 collapsed;

50 Fig. 9 is a sectional view with parts in elevation, taken on the line 9—9 of Fig. 7;

Fig. 10 is a perspective view looking into a partly collapsed box of the kind shown in Figs. 7 to 9, but with no honeycomb unit in place; and

55 Fig. 11 is an elevation of the framed collapsible

honeycomb insert used in connection with the collapsible box of Figs. 7 to 10.

Referring to the numerals on the drawings, the imitation grass is made from a section of honeycomb paper such as shown in Fig. 5. The lengths 5 of paper from which the honeycomb is made are slitted in their upper portions as indicated at 10 in Fig. 6, and the unslitted lower portion of each length of paper is provided at spaced intervals with a glue area 11 whereby it may be 10 united to the next adjacent length of paper, to form honeycomb cells, these glue areas being indicated by the same reference character, 11, in Fig. 5. A section of the honeycomb thus constructed may be compacted or expanded, in a 15 well-known manner, and when it is expanded the upper end will present the appearance of grass, as suggested by Figs. 3, 4, 7 and 9.

Such a honeycomb section may be used in various ways, but I have shown how it may be 20 utilized in the making of an Easter basket. In Figs. 1 to 5 inclusive I show a more or less conventional form of pasteboard box, which is collapsible for shipping as indicated in Figs. 1 and 2, and expandable to the final form shown in Fig. 3. 25 Here the walls 12, which are the opposed side walls of the expanded box, have glued to them, respectively, by means of glue areas 11' shown in Fig. 5, the outermost lengths of paper constituting the honeycomb section, in such fashion that when the box is collapsed the honeycomb is compacted between them, and so that when these walls are brought to the Fig. 3 position the honeycomb will be expanded between them, with the lower edges of its component lengths of paper 30 upon or close to the bottom of the box (comprising box sections 13) and the upper slitted portions reaching almost to the top of the box and presenting the appearance of grass, sufficiently for the purposes of an Easter basket. 35

In Figs. 7 to 9 the box or nest has a generally triangular form. It is therefore not feasible to glue the honeycomb to some two interior walls of the box, and accordingly the honeycomb has two of its sides glued to adjacent sides 14 of a frame or holder, which holder when expanded is triangular and of a size to fit the box, the third side of the holder having no direct connection with the honeycomb and having bend lines 15 separating it from the sides 14 and having also a median bend line 16 so that when the first two sides are brought towards each other with the honeycomb compacted between them the two halves of the third side will also approach each other; thus the honeycomb and its frame 40 45 50 55

may be shipped flat inside the collapsed box; and when the box is expanded, the expanded honeycomb is set into it, with the visual result suggested by Fig. 7.

5 In order to bring the box of Figs. 7 to 10 from collapsed or partially collapsed to expanded condition, the sections 17, 18, 19 and 20 (Fig. 10) are moved forward and (necessarily) downwardly with respect to the walls 21 to which they are connected, whereupon the sections 17 and 18 become the front wall or third side of a triangular box of Fig. 7, and the sections 19 and 20 become the bottom thereof.

I claim:

- 15 1. As a new article of manufacture a container, and a honeycomb paper unit secured between walls of said container immediately above the bottom thereof, said unit being made up of component lengths of paper which are slitted and unconnected as to their upper edge portions and unslit and united together at spaced intervals as to their lower edge portions, said unit serving as a support for articles deposited in said container.
- 20 2. As a new article of manufacture a collapsible container, and a honeycomb paper unit secured between walls of said container immediately above the bottom thereof, said unit being made up of component lengths of paper which are slitted and unconnected as to their upper edge portions and unslit and united together at spaced intervals as to their lower edge portions, said unit serving

as a support for articles deposited in said container, and being collapsible within walls of said container.

3. As a new article of manufacture a container, and a honeycomb paper unit secured between walls of said container immediately above the bottom thereof, said unit having upstanding strip-like portions simulating grass, said unit serving as a support for articles deposited in said container. 5

10 4. As a new article of manufacture a container, and a honeycomb paper unit secured between walls of said container immediately above the bottom thereof, said unit having upstanding strip-like portions, said unit serving as a support for 15 articles deposited in said container, said strip-like portions being movable under the weight of deposited articles to simulate matted grass.

5. As a new article of manufacture an open top collapsible container, and a honeycomb paper unit secured between walls of said container immediately above the bottom thereof, said unit having a bottom portion resistant to downwardly applied weight whereby said unit serves as a support for articles deposited in said container, and 20 said unit having an upper portion, made up of upstanding strips offering little resistance to the downwardly applied weight of such articles, said upstanding strips simulating grass, said unit being collapsible within walls of said container. 25 30

HENRY E. LUHRS.
